HAND CARD

Application filed May 28, 1927. Serial No. 195,115.

This invention relates to hand cards and has for its principal object to provide a hand card comprising a body and a novel handle construction therefor.

5 In order to give an understanding of the invention I have illustrated in the drawings a selected embodiment thereof which will now be described after which the novel features will be pointed out in the appended 10 claim.

In the drawings Fig. 1 is a perspective view of a hand card embodying my invention;

Fig. 2 is a section on the line 2—2, Fig. 1;

15 Fig. 3 is a fragmentary under side view of the handle;

Fig. 4 is a perspective view of the handle.

The hand card comprises the usual body 1 in the form of a board on one face of which is located a sheet of card clothing 2 secured to 20 the body and to one edge of which is secured a handle indicated generally at 3.

It has been the common practice to make the body 1 of a piece of board which, of course, is relatively thin and which is liable 25 to crack or split longitudinally after being used a relatively short time.

The body 1 is made of several plies of wood which are glued together. In the illustrated embodiment the body comprises three plies 30 4, 5, 6. These various plies, which are preferably made of wood, are glued together so as to make a laminated structure and in doing so I preferably arrange the grain of the intermediate ply 5 so that it extends at right 35 angles to the grain of the outer plies 4 and 6. Thus it will be seen that the grains of contiguous plies extend transversely to each other.

The body is further made with a slight curvature from the edge 7 to the edge 8 40 and in making the laminated body a coating of glue or other suitable adhesive will be applied to the meeting faces of the plies and then they will preferably be pressed firmly together in a press which will give them the 45 desired curved shape. Thus the curved shape is given to the body before the glue dries with the result that when the glue or other adhesive has thoroughly dried the body will have a permanently curved shape and the internal stress of each ply due to this curvature

will therefore be the same. The ply 4 is made a little thinner at the edge 7 than at the other edge as shown clearly in Figs. 1 and 2.

55 The handle 3 is of novel construction. It comprises a metal section 9 which is secured to the edge 8 of the body 1 and a wooden section 10 which is anchored in the metal section. The metal section is formed with a recess 11 into which the end 12 of the wooden section 10 is inserted, said wooden section being retained in place by means of the rivet 13.

60 Said metal section 9 is also formed with the two flanges 14, 15 between which the edge 8 of the body is received. The flange 14 overlies the back face of the body and the flange 15 is on the under face thereof. Said flange 15 is of less length than the flange 14 and is received in a recess 16 formed in the under 65 face of the body and of sufficient depth so that the outer face of the flange 15 comes flush with the under face of the body 1. The handle is secured to the body by suitable rivets 17, 18, the rivet 17 extending through

70 the two flanges 14 and 15 and the rivet 18 being situated beyond the flange 15 and extending through the flange 14 and the body 1. The flange 15 is also of less width than the flange 14 and the handle is formed with the wings 19 75 that present surfaces 20 that bear against the edge 8 of the body 1. When the rivet 17 is tightened the edge 8 of the body is clamped between the two flanges 14 and 15 and this together with the rivet 18 which is spaced some 80 distance from the rivet 17 makes a strong connection between the handle and the body.

85 The metal portion 9 of the handle is formed on its under side with a recess 21 and is provided with a pin 22 which extends 90 through the handle and across the recess.

95 A finger-receiving loop 23 of flexible material is connected to the pin 22, one end of the loop entering the recess 21 and encircling the pin 23. In using the card the fingers of the operator will be inserted through the loop 23 and said loop provides means by which the card may be manipulated without danger that the hand of the operator will 100 slip off the end of the handle.

While I have illustrated herein a selected embodiment of my invention I do not wish to be limited to the constructional features shown other than as set forth in the claim.

I claim:

- 5 A hand card comprising a body, a handle having a metal section and a wooden section, the metal section presenting two flanges between which one edge of the body is received, the flange on the back of the body being longer and wider than the flange on the front of the body, two rivets uniting the longer flange to the body, one of said rivets passing through both flanges, said metal section having a recess in its under side, a pin extending across said recess and a loop of flexible material encircling said pin and through which the fingers of the operator's hand may be inserted.
- 10
- 15
- 20

In testimony whereof, I have signed my name to this specification.

WILLIAM A. DUTTON.
